UNITED STATES PATENT OFFICE

2,285,344

SUPERCHARGED INTERNAL COMBUSTION
ENGINE

Elwyn Ivo Banks Marples and Horace Nathaniel Gorrell, Bristol, England, assignors to The Bristol Aeroplane Company Limited, Bristol, England, a British company

Application February 13, 1941, Serial No. 378,826
In Great Britain February 13, 1940

10 Claims. (Cl. 123—119)

This invention relates to supercharged internal-combustion engines, for aircraft, of the kind comprising two blowers in series, at least one of which can be rendered operative or inoperative at will, and a carburettor between the blowers. For example, the second-stage blower may be permanently geared to the engine and the first-stage blower may be driven from the engine through clutch-mechanism which may be engaged or disengaged at will. Alternatively, the first-stage blower may be driven by a turbine through which the exhaust gases of the engine are discharged; in this case the first-stage blower may be rendered inoperative by by-passing the exhaust gases so that they are discharged without driving the turbine. At low altitudes of flight the first-stage blower is out of action and the combustion air merely passes through it to the carburettor and second-stage blower. Above a certain altitude of flight the pilot renders the first-stage blower operative whereby the extent of supercharge is increased.

The object of the invention is to provide a form of boost and throttle control which is effective for all conditions of operation.

According to this invention there is provided in an internal-combustion engine, the combination with two supercharging blowers arranged in series, of a throttle-valve on the inlet of each blower, and means which selectively renders either valve operative and holds the other in or near its fully-open position. Preferably the invention comprises the combination with an engine-driven blower, an auxiliary blower and means for rendering operative the auxiliary blower, of an operative connection between said blower and the throttle-valves, as above described, whereby the valve of the auxiliary blower is held open when that blower is inoperative. The auxiliary blower may be driven by the engine through a clutch, in which case there is provided the combination with the clutch-control lever of a rocking shaft operated thereby to connect a single throttle-control lever to one or other of the throttle-valves.

According to another feature of this invention, the arrangements above described are applied to throttle-valves controlled by a "variable-datum boost-control." Such apparatus comprises a pressure-responsive device, such as a collapsible capsule, subjected to the pressure in the engine-induction system at the discharge side of the second-stage blower, a connection between the said device and the engine throttle-valve and means operable by the pilot to adjust the said

device in such manner that, despite variations in conditions of flight below a certain altitude, the valve is automatically maintained at such a setting that the pressure of the charge admitted to the engine cylinders corresponds to the position of the pilot's adjusting-means. The connection between the pressure-responsive device and the throttle-valve is usually by way of a relay and there may or may not be a direct mechanical connection between the pilot's lever and the throttle-valve. Where such interconnection exists the action of the pressure-responsive device is superimposed upon it.

The invention also comprises various arrangements of variable-datum boost-control, as hereinafter described.

In the accompanying drawings:

Figure 1 is a purely diagrammatic representation of the apparatus according to the present invention, embodying a single pressure-responsive device for the variable-datum boost-control, and two hydraulic relay-devices selectively controlled thereby for operating the throttle-valves.

Figure 2 is a diagrammatic representation of an arrangement including a single pressure-responsive device and hydraulic relay, with mechanical means for selectively operating the two throttle-valves.

Figure 3 is a diagrammatic representation of an arrangement including a single pressure-responsive device and two hydraulic relays, and

Figures 4, 5 and 6 are diagrammatic representations of arrangements, each embodying two pressure-responsive devices and two hydraulic relays with various means for effecting the selective operation.

Referring first to Figure 1, a radial-cylinder engine is indicated generally by the reference 10 having cylinders 11 supplied through an intake 12 from an engine-driven supercharging blower 13. A throttle-valve 14 is situated in the intake to this blower, and the air-supply to the blower takes place through a carburettor 15 and an auxiliary blower 16 having a throttle-valve 17 in its intake. The auxiliary blower 16 may be driven in any convenient manner, through a clutch from the engine or by an exhaust-gas turbine together with any suitable means for rendering such drive operative or inoperative at will, such selection being made by the pilot of the aircraft according to the power requirements or altitude of flight. Other details, such as an intercooler between the two blowers, will be used but are not concerned with this invention and are, therefore, not illustrated.

A variable boost-control for the engine comprises a collapsible capsule 18 situated in a chamber 19 which is connected to the engine-intake 12 so that the pressure therein is operative on the capsule. A further control of the capsule is effected by the cam 20 on a pilot's control lever 21, the position of the lever indicating the datum-setting for the capsule in the usual manner.

The pilot's lever 21 is connected by a toggle-linkage 22, 23 to the throttle-valve 14, also in the known manner, and the capsule 18 is also rendered operative on the throttle-valve through a hydraulic relay-device. The lower end of the capsule is coupled to a rod 24 on which there is pivotally mounted at the middle of its length a lever 25, and the ends 26, 27 of this lever respectively engage controlling valves 28, 29 of hydraulic relay-devices; these valves are of the usual type controlling the admission of a pressure-fluid by a conduit 30 to two cylinders 31, 32, and the exhaust therefrom by conduits 33. The cylinder 31 contains a piston 34 provided with a leak-hole 35 and having its piston-rod 36 connected by a link 37 to the joint of the toggle 22, 23.

The cylinder 32 contains a piston 38 with a leak-hole 39 and its piston-rod 40 is connected through a linkage 41, 42, 43 with the throttle-valve 17.

Each of the valves 28, 29 is provided with a controlling spring which tends to move it to its uppermost position, and a rocking-shaft 44 is provided with two cams 45, 46 which are adapted to engage the upper ends respectively and alternatively of the valves 28, 29 so as to press them downwards. As illustrated, the cam 46 is holding the valve 29 downwards in such a position that the pressure-fluid is admitted to the underside of the piston 38 so as to force it to the top of its stroke and the cam 45 is turned to a position which is clear of the valve 28 to leave it free. This valve is, therefore, controlled by the lever 25 which, having its other end 27 held in a fixed position, determined by the cam 46, is under the control of the capsule 18, so that movements of the lower end of the capsule upwards or downwards are imparted to the valve 28 in the normal manner of a relay-control by the pressure existing in the engine-intake 12.

By rotating the rocking-shaft 24, the cam 46 can be disengaged from the valve 29 and the cam 45 engaged with the valve 28, so that the latter is held inoperative and the former is controlled in accordance with the pressure existing in the engine-intake 12.

The rocking-shaft 44 is connected by a suitable linkage 47, 48 to a manually controlled device 49 which is indicated as a lever, and is interconnected with the driving means or control thereof for the auxiliary blower 16, and the arrangement is such that when the blower 16 is inoperative, the cam 46 is engaged with the control-valve 29 so that it is inoperative.

At low altitudes of flight, the blower 16 is rendered inoperative by the lever 49 and, as explained above, the valve 29 is thereby held in such a position that the piston 38 is held in its uppermost position in which the valve 17 is held in its open position and is not controlled in any way by the capsule 18, and the variable-datum boost-control operates only upon the throttle-valve 14. Thus, the pressure of the air delivered by the blower 13 maintains a definite relationship to the setting of the pilot's lever 21 in the usual manner.

When a predetermined altitude is reached, the 75

lever 49 is operated by any suitable means to engage the blower 16 to provide a first stage of compression. The cam 46 thereupon releases the valve 29, and the cam 45 engages the valve 28 to press it downwards to such an extent that the relay-piston 34 is moved to its upper position in which it opens the valve 14 to a substantially fully-open position. The variable-datum boost-control is now operative through the lever 25 on the valve 29 and thereby on the throttle-valve 17 to maintain, in the usual manner, a definite boost-pressure for each setting of the lever 21. In this setting a mechanical connection 22, 23 between the lever 21 and the valve 14 is still operative to cause movements to the valve 14 when the pilot adjusts the lever 21 but the linkage 37, 22, 23 is so designed that such movements are small, and that in its mean position the throttle-valve 14 is fully open. This arrangement, therefore, provides that when only the blower 13 is in operation, the variable-datum boost-control is operative on the throttle-valve 14, and the throttle-valve 17 is held in its fully-open position, and that if the blower 16 is rendered operative to give the primary or first-stage of compression, the valve 14 is held in a substantially fully-open position and the variable-datum boost-control operates only the throttle-valve 17 so that the control, so far as the pilot is concerned, is always the same whether one or two stages of compression are used.

In the alternative form of this invention illustrated in Figure 2, a single variable-datum boost-control operates selectively on the two throttle-valves; the collapsible capsule 50 controls in the usual manner, through the valve 51, the relay-piston 52, and the latter is connected through the link 53 with a toggle linkage 54, 55 whereof one member 55 is connected to the pilot's control-lever 56 and the other link 54 is connected to the fulcrum 57 of a rocking-lever 58. The ends of this lever 58 are connected respectively to the first and second throttle-valves 59, 60 and the selection between the two valves is effected by means of cams 61, 62 on a rocking-shaft 63 which alternatively engage abutments 64, 65 to hold one or other throttle-valve in its fully-open position. When thus held, one end of the rocking-lever 58 is held stationary, and the variable-datum boost-control operates upon the other valve through the lever 58 in the normal manner. The rocking-shaft 63 controls, through an arm 66, the clutch or other means which renders the first-stage blower operative or inoperative as desired.

In the alternative arrangement according to this invention illustrated in Figure 3, a single collapsible capsule 67 for a variable-datum boost-control operates two valves 68, 69 similarly and simultaneously, these valves, in turn, controlling respectively two relay-pistons 70, 71. The relay-piston 70 is connected to the mid-point of a toggle-linkage 72 connecting the pilot's control lever 73 with one of the throttle-valves 74, and the relay-piston 71 is connected through any suitable linkage with the second throttle-valve 75.

The selective operation of the valves 74, 75 is effected by controlling the supply of pressure-fluid to the relay-cylinders; the pressure-fluid is supplied through the pipe 76 and a valve 77 by which it can be admitted to one or other of the pipes 78, 79 supplying the relay-cylinders respectively. The controlling lever 80 for this valve is interconnected with the clutch or other device which renders the auxiliary blower opera-

tive or inoperative as desired. When the clutch is hydraulically controlled, the interconnection aforesaid may be provided by supplying pressure-fluid to the clutch through the pipe 81 so that when the valve 77 is in the position shown, pressure-fluid is delivered to the pipes 79 and 81 so that the clutch is engaged and the relay-piston is supplied with pressure-fluid; no pressure-supply is given to the valve 88 and relay-piston 70 and the spring 82 forces the piston 70 to the upper limit of its stroke, holding the valve 74 in substantially its fully-open position.

In yet another modification of this invention as illustrated in Figure 4, two separate variable-datum boost-controls, one for each throttle-valve, can be used. In this figure, the two collapsible capsules are shown at 83, 84 and the pilot's control-lever 85 operates simultaneously on both of them through cams 86, 87 by means of the linkage 88a. Each capsule controls the relay-pistons 88, 89 respectively, in the usual manner, and the pistons, in turn, operate the two throttle-valves 90, 91.

The selective operation of the two relays is effected by means of a valve 92 controlling the admission of pressure to the capsule chambers 93, 94. A pipe 95 from the delivery side of the main blower, or the induction pipe of the engine, and a second pipe 96 connected to the inlet side of the main blower, are selectively connected to the chambers 93, 94 by the valve 92. In the position shown, the pipe 95 is connected to the chamber 93 so that the capsule 83 is subjected to the boost-pressure of the engine and operates in the normal manner. The chamber 94, however, is connected to the induction side of the main blower by the pipe 96 and the low-pressure at that point permits the capsule 84 to expand so that it moves its valve downwards, thereby applying pressure to the under side of the piston 88 and moving the valve 91 to its fully-open position. When the valve 92 is changed over to reverse the connections of the pipes 95, 96 with the chambers 93, 94, the relay 88 is thereby rendered inoperative and the valve 90 is opened, whilst the normal boost-control is effected on the valve 91.

Figure 5 illustrates yet another modification of the present invention which is similar to that illustrated in Figure 4, in that two variable-datum boost-controls are used, one for each throttle-valve. The chambers 97, 98 for the two collapsible capsules are both subjected to the pressure in the inlet-manifold of the engine, and their selective operation is determined by controlling the supply of pressure-fluid to their relay-valves 99, 100 respectively by means of a valve 101 which operates in the same way as the valve 77 described with reference to Figure 3. As shown, pressure-fluid is being supplied to the valve 99, but is cut off from the valve 100 and the spring 102, therefore, forces the piston 103 to its uppermost position, moving the throttle-valve 104 to its fully-open position, the normal control being maintained on the other throttle-valve 105.

In yet another modification illustrated in Figure 6, two separate variable-datum boost-controls are again used, and the two collapsible capsules 106, 107 are both subject to boost-pressure continuously, and they are provided with the usual controlling cams 108, 109 operated by the pilot's control-lever 110. A mechanical override for each of the cams is provided by tappets 111, 112, respectively, which are operated by a

lever 113 interconnected with the driving control for the auxiliary blower. When the auxiliary blower is rendered inoperative, as shown in Figure 6, the tappet 112 moves the capsule 107 downwards from engagement with its cam 109 and thereby moves the relay-valve 114 to its lowermost position, in which case the hydraulic relay operates to set the throttle-valve 115 in its fully-open position. The movement of the lever 113 which effects this operation simultaneously lifts the tappet 111 clear from its capsule 106 so as to leave the latter under the control of its cam 108 and thereby effect the normal control on the throttle-valve 116. When the lever 113 is moved to its other position to render the auxiliary blower operative, the tappet 112 is lifted clear of its capsule and the tappet 111 is engaged with its capsule 106 to depress it and thereby cause the throttle-valve 116 to be moved to its fully-open position whilst the normal boost-control is operative on the auxiliary throttle-valve 115.

We claim:

1. In an internal-combustion engine the combination of two supercharging blowers arranged in series, a throttle-valve on the inlet of each blower, and means which selectively renders either valve free to be operated by the usual controls and holds the other valve in or near its fully-open position.

2. Apparatus as set forth in claim 1 comprising an engine-driven blower, an auxiliary blower, means for rendering operative the auxiliary blower, and an operative connection between said means and the throttle valves, whereby the valve of the auxiliary blower is held open when that blower is inoperative.

3. In an internal combustion engine the combination of two supercharging blowers arranged in series, a throttle valve on the inlet of each blower, means which selectively renders either valve free to be operated by the usual controls and holds the other valve in or near its fully open position, said blowers comprising an engine driven blower, and an auxiliary blower, an operative connection between said means and the throttle valves whereby the valve of the auxiliary blower is held open when that blower is inoperative, said blower being driven by the engine through a clutch, the combination with the clutch control lever, of a rocking shaft operated thereby to connect a single throttle control lever to one or other of the control valves.

4. In an internal combustion engine the combination of two supercharging blowers arranged in series, a throttle valve on the inlet of each blower, means which selectively renders either valve free to be operated by the usual controls and holds the other valve in or near its fully open position, said blowers comprising an engine driven blower, and an auxiliary blower, an operative connection between said means and the throttle valves whereby the valve of the auxiliary blower is held open when that blower is inoperative, said throttle valves being controlled by a variable-datum boost control.

5. Apparatus according to claim 4, comprising a single collapsible capsule subjected to the induction pressure in the engine manifold, and operating on a floating lever at the middle of its length, two relay-devices whereof the valves are coupled respectively to the ends of said lever, and the relay-pistons are coupled respectively to the two throttle-valves, a rocking-shaft having two cams which alternatively engage the ends of

the floating lever and rock it to a limiting position wherein the free end is operated by the capsule and controls its relay-valve, and a connection between said rocking-shaft and the drive of the auxiliary blower.

6. Apparatus according to claim 4, comprising a single collapsible capsule, a single relay device controlled thereby and means for selectively coupling it to one or other of the throttle-valves.

7. Apparatus according to claim 4, comprising a single collapsible capsule, two relay devices controlled thereby, and operating respectively on the two throttle-valves, means for selectively supplying pressure-fluid to one or other of said relays, and means whereby the relay which is not thus energized, moves to its limiting position to open its valve.

8. Apparatus according to claim 4, comprising a separate and complete variable-datum

boost-control for each throttle-valve and means for selectively subjecting the collapsible capsule thereof to the induction pressure in the engine manifold.

9. Apparatus according to claim 4, comprising a separate and complete variable-datum boost-control for each throttle-valve and means for selectively supplying pressure-fluid to the relay-devices thereof.

10. Apparatus according to claim 4, comprising two complete variable-datum boost-controls, one for each valve, tappets arranged selectively to engage the collapsible capsules and disengage one or other from its datum-varying cam, said tappets being operated by or with the control means for the drive of the auxiliary blower.
